Inventor,
Harry Matthes.

United States Patent Office.

HENRY MATTHES, OF CAMBRIDGEPORT, MASSACHUSETTS.

Letters Patent No. 79,669, dated July 7, 1868.

IMPROVEMENT IN STEAM-GAUGES.

The Schedule referred to in these Letters Patent and making part of the same.

TO ALL WHOM IT MAY CONCERN:

Be it known that I, HENRY MATTHES, of Cambridgeport, in the county of Middlesex, and State of Massachusetts, have invented certain new and useful Improvements in Steam-Gauges; and I do hereby declare that the following is a full, clear, and exact description of the construction and operation of the same, reference being had to the annexed drawings, making a part of this specification, in which—

Figure 1 shows the usual steam-gauge with my improvements attached, the portion containing said improvements being shown in elevation and section.

Figure 2 represents the conical wire-spring.

Figure 3 represents the corrugated metallic disk.

The improvements which I have made in steam-gauges do not change the common form and arrangement of such articles, and can be readily applied to many of them, with slight alterations and expense. The most approved mode of constructing them at the present time is to allow the steam to press upon a circular disk of rubber, firmly secured and packed at its edges, by screwing the parts of the box containing it together. The rubber is then brought in direct contact with the edges of a conical riband-spring, to the centre of which is attached a rod which operates the indicating-mechanism.

My invention consists, first, in substituting for the rubber a disk of flexible metal; second, in substituting for the riband-spring a conical spring made of wire, which tapers from one end to the other.

In the gauge shown in the drawings, A represents the metal disk; B, that portion of the coupling through which the steam passes; α , a washer, which is pressed, when the portions B and C of the coupling are screwed together, against the part C and the disk A, the said washer and the screw being thoroughly packed with red lead or other suitable material. The centre of the disk A presses against a rod, d, which operates the indicating-mechanism, and to which is attached the conical tapered wire spring S. The operation will be plain to all skilled in the art.

The flexible disk is made of five parts of eighteen-carat gold, four parts of silver, and one part of copper, and this is the best alloy known to me. The disk should be corrugated or dished, to allow the necessary motion of its centre, and it is preferable to make it thicker at the part which bears against the spring.

The spring is made of round wire, instead of flat metal, to obviate the objection to which the riband-spring is liable, of cutting the disk which is pressed against it by the steam, and the wire is tapered, to make its action more regular and uniform. The taper should be wrought to make the end of the wire where it is attached to the rod d about one-half the diameter of the other end.

I do not claim the use of flexible corrugated metal generally, to transmit the pressure of the steam to the indicating-mechanism; but having thus described my invention,

What I claim as new, and desire to secure by Letters Patent, is—

1. The arrangement of the cap B, the disk A, and washer α , substantially as and for the purpose specified.
2. A flexible disk for steam-gauges, when constructed of the materials and in the proportions substantially as described.
